ROTATING CLOTHES DRIER

Ransaeller J. Jenks, Lewiston, Idaho

Application September 27, 1937, Serial No. 165,914

5 Claims. (Cl. 34—26)

The object of this invention is to provide a novel mechanism for drying clothes.

It is a feature of the invention to revolubly mount the clothes to be dried and to direct upon the clothes an air blast or current in such a manner as not only to dry the clothes but also to cause rotation thereof so as to bring all the clothes within range of the path of the drying air.

10 It is also a feature of the invention to provide air directing and drying means which itself is rotatively mounted so that if it is desired that the clothes shall remain stationary, the air directing means may revolve as a result of the re-15 bound thrust of the drying air against the clothes.

It is also a feature of the invention to provide positive driving means for causing rotation of either the clothes or the air directing means, 20 and to provide devices for preventing rotation of either of said instrumentalities.

The invention involves a novel form of centrally disposed standard about which the clothes and the air directing means may rotate, the standard being extensible and having floor and 25 ceiling engaging heads for rendering the standard stable when in an operating position.

The invention has many other features and objects which will be more fully described in 30 connection with the accompanying drawing and which will be more particularly pointed out in and by the appended claims.

In the drawing:—

Fig. 1 is a vertical sectional view of the preferred form of my drying mechanism.

Fig. 2 is a view in elevation of the upper portion of the mechanism shown in Fig. 1.

Fig. 3 is a diagrammatic view of one circuit that may be employed.

40 Fig. 4 is a detail plan view of one of the rack bars showing how it is connected with the standard.

Fig. 5 is a view partly in section and partly in elevation of the air directing means.

45 Like characters of reference designate similar parts throughout the different figures of the drawing.

Referring to the specific form shown, I designates a floor engaging head which may be provided with one member 2, of a ball race for anti-friction balls 3, or roller bearings which ever may be desired. The head 1 has a journalling post 4, extending upwardly therefrom as shown.

A rack carrying sleeve 5 has its lower end rotatively journalled on said post 4 and is flanged

5 at 6, to afford the remaining member of the ball race for balls 3, to reduce friction, as will be clear. The upper end of said sleeve 5, is flanged at 7, to afford a supporting end for a part to be later described. A pulley 8, is suitably fixed to sleeve 5, and may be driven from any suitable source of power by means such as a belt 9, as one mechanical expedient of causing rotation of the clothes.

Reference will next be made to that portion of the mechanism above the rack sleeve.

What I will term an air directing sleeve 10, is provided with a flanged thrust end 11, adapted for endwise engagement with the flanged thrust end 7, of sleeve 5. A pulley 12, is suitably secured 15 to sleeve 10 and may be driven by a belt 13, operated from any suitable source of power. A ceiling engaging head 14 of hexagonal form, is adapted to abut against the ceiling 15 and is provided with an internally threaded stud 16 20 extending downwardly therefrom, as shown in Fig. 1, and which inwardly telescopes sleeve 10. A sustaining rod 17 has a lower polygonal end 18 that is socketed in the top of post 4, so that said rod will not only be supported thereby but will also be non-rotatively connected therewith. Said rod 17, has an enlarged alining section 19 which journals the upper end of sleeve 5 and the lower portion of sleeve 10 not only to aline the same but to thereby facilitate selective rotary movement thereof. While I have not shown anti-friction bearings at the juncture of the various parts having thrust engagement, except for the lower end of sleeve 5, it will be understood that such expedients may readily be employed and will be dictated by mechanical skill, in view of this disclosure. Said rod 17, is provided with an exteriorly threaded adjusting section 20, having threaded engagement with the stud 16, so that by turning head 14, rod 17 can be lengthened or shortened in accordance with the direction in which head 14 is turned. When the adjustment has been made, as shown in Fig. 1, rod 17 functions as a sustaining rod under lengthwise compression to sustain heads 1 and 14 in firm engagement with the floor A and ceiling 15.

The advantage of this construction will be clear from the fact that all the stabilizing stress is taken by rod 17 and heads 1 and 14, thereby leaving the revolving parts free from any friction due to stabilizing stress.

As a means of selectively preventing rotation of either sleeve, I have shown devices which may consist of winged pins 21 and 22. Pin 21 is 55

adapted to be inserted through sleeve 5, into post 4, to prevent rotation of sleeve 5, and of course it can be withdrawn to permit rotation of said sleeve. Pin 22, is inserted through sleeve 10, into 5 the non-rotatively supported rod 17, and preferably into section 19 thereof, to prevent rotation of sleeve 10, and can be withdrawn to permit rotation thereof. This is a further reason why rod 17 is non-rotatively connected with post 4, in 10 addition to the fact that such connection permits lengthwise adjustment of rod 17 by turning head 14.

The rack sleeve 5 has a plurality of clothes racks radiating therefrom and since each set of racks 15 is identical in form and function only one need be described in detail.

Rack bar rings 23 and 24 are secured to sleeve 5 in vertical spaced relation and each has flanges, indicating at 24' and 25, respectively, with notched 20 outer ends 26 and 27, adapted to receive laterally projecting pins as shown at 28, whereby the inner ends of rack bars 29 and 30 are supported. Bar 29, is longer than bar 30, and has its outer end notched at 31. A spacing bar 32 is pivoted at 25 33 and 34, to bars 29 and 30, and this pivotal connection at 33 is radially inwardly from the free end of bar 29, as will be clear from Fig. 1. A supporting rod 35 is pivoted at 34, to bar 30, and at 36 to a ring 37, that is secured to sleeve 5.

30 I have shown the spacing bar 32, notched at 38, thus providing a supporting means for a line or cord 39, adapted to extend about the bars 32 as a supporting means for clothes to be dried. A line or cord 40, is disposed in notches 31, for 35 a similar purpose. Thus an inner and an outer circle of clothes can be hung from these lines, in addition to the clothes which are hung on the radially disposed bars 29 and 30 as will now be clear, and from which it will be seen that the 40 capacity is very greatly enlarged. Clothes disposed in this manner provide the desired reaction for a stream of air adapted to function both as a drying and as a propulsive medium, as will presently appear.

45 Reference will next be made to the air direction means and to the manner in which it functions.

Sleeve 10 is provided with a radially disposed boss 41 in which a pipe or tube 42 is disposed 50 and held by means such as winged nut 43. A collar 44 is carried by said pipe 42 and secured by a screw 45. Contact rings 46 and 47, are connected by hollow posts 48 and 49 with said collar 44 and suitably insulated therefrom, and 55 are disposed in concentric relation to the standard, as shown. Suitable brushes 50 and 51, fixedly mounted at 52 and 53, respectively, make electrical contact with said rings as the latter either rotate or remain stationary. A source of current 54, has a lead 55 extending from one pole thereof to brush 50, and a lead 56, extending to brush 51, to supply current thereto. Lead 57 extends from ring 46 through support 48 and pipe 42, to one terminal 58, of an electric fan 59. 60 Lead 60 extends from ring 47, through support 49 to the other terminal 61, of fan 59, thereby completing the circuit, through pipe 42, which of course is suitably insulated from the leads extending therethrough.

70 Fan 59 is mounted on a collar 62 which is adjustable on pipe 42, and which can be held in an adjusted position by screw 63. It will be seen that the fan may be adjusted longitudinally of pipe 42, which is radially of the drier, and from 75 Fig. 2, it will be clear that fan 59 can be set at such

an angle that instead of the air blast being directed straight downwardly, it can be directed at an angle to the vertical thereby causing rotating movement of either sleeve 5, carrying the racks, or sleeve 10, carrying the fan. A switch 64, is interposed in the circuit, as shown in Fig. 3. In Fig. 5, I have shown how the pipe 42 is slotted at 65 to permit the leads to extend to the fan and afford clearance for longitudinal and 10 rotative adjustment of the collar 62.

While the operation may be clear from the foregoing, it will be briefly recapitulated as follows:—

If the invention is incorporated in a normally unstable form of standard, as shown, then the standard is positioned with head 1 engaging the 15 floor and head 14 is then rotated until the rod 17 causes engagement of head 14 with the ceiling 15, as shown. If positive drive of the sleeves is resorted to, then provision for operating the belts must be made, but I have successfully operated 20 the drier without a positive drive and therefore do not regard the latter as essential. However, if a positive drive is used, either of the sleeves 5 or 10, may be locked in a fixed position by devices 21 or 22, to permit the other sleeve to be 25 rotated, as previously explained. In some cases, it may be desirable to rotate the clothes and hold the fan stationary, and in other cases, it may be desirable to cause the fan to rotate and hold the clothes racks stationary.

30 It will be understood that if the fan is not rotated, then the electrical contact means shown and described can be omitted.

If the positive drive is omitted, then the clothes racks can be caused to revolve by setting the fan 35 59 at an angle, as shown in Fig. 2, so that the air blast will act upon the clothes not only to dry the same but also to rotate the racks and the sleeve 5 thereof. Because of the inner and outer 40 circle of clothes on the inner and outer cords 39 and 40, respectively, the air from the fan is very effective, and the clothes on the bars 30 and 29, which are radially disposed, will perform the propulsive thrust necessary to revolve the racks as 45 the air acts upon said clothes, it being understood that pin 22, is inserted to hold the sleeve 10 from rotating.

When pin 22 is withdrawn so that sleeve 10 can 50 rotate, and the axis of the fan is at an angle to the vertical as shown in Fig. 2, then due to the horizontal component of the thrust of the fan, the sleeve 10 and the fan will rotate around the aligning section 19.

It will be understood that I use the phrase "air 55 directing means" generically to also include an air heater if such expedient is desired instead of or in addition to a fan, this phrase being broadly construed in the claims.

It is believed that my invention will be fully 60 understood from the foregoing description, and while I have herein shown and described one specific form of the invention, I do not wish to be limited thereto except for such limitations as the claims may import.

I claim:

1. In a clothes drying mechanism, a central 65 standard having floor and ceiling engaging heads for rendering said standard stable, a sustaining rod supported on and being non-rotatively connected with said floor head and having threaded 70 extensible connection with said ceiling head, a rack carrying sleeve revoluble about said rod and rotatively supported on said floor head near the lower end of said sleeve and said sleeve having a series of clothes racks, a sleeve having air direct- 75

ing means and revolvably supported on said rack sleeve, said rod having an alining section journaling said sleeves, drying means for revolving either of said sleeves, and devices for preventing rotation of either of said sleeves.

5 2. In a clothes drying mechanism, a central standard having floor and ceiling engaging heads for rendering said standard stable, a sustaining rod supported on and being non-rotatively connected with said floor head and having threaded extensible connection with said ceiling head, a rack carrying sleeve revolvably mounted on said floor head near the lower end of said sleeve and surrounding said rod and having clothes racks, 10 a sleeve having air directing means and revolvably supported on said rack sleeve, and said rod having an alining section journaling said sleeves at the juncture thereof.

15 3. In a clothes drying mechanism, a central standard provided with a revolving sleeve having radiating clothes racks thereon, and said standard having an air directing sleeve revolvable thereon and provided with adjustable air directing means adapted to be set at desired angles to direct air upon the clothes on said racks to dry the clothes and cause rotation of either of said sleeves to bring all the clothes into range of the air from 20 said means, and devices for preventing rotation of either of said sleeves.

4. In a clothes drying mechanism, a central standard provided with a revolving sleeve having radiating clothes racks thereon, and said standard having an air directing sleeve revolvable thereon and provided with adjustable air directing means 5 adapted to be set at desired angles to direct air upon the clothes on said racks to dry the clothes and cause rotation of either of said sleeves to bring all the clothes into range of the air from 10 said means, and devices coacting with said standard for preventing rotation of either of said sleeves.

15 5. In a clothes drying mechanism, a floor head for frictionally engaging a floor of a room and said head having a journaling post, a sustaining rod non-rotatively seated in said post and having an alining section, a ceiling head for frictionally engaging a ceiling of the room and having a stud in threaded engagement with said rod for extension of said heads for rooms of different height, 20 a rack carrying sleeve journalled about said post and alining section and rotatively supported on said floor head, and an air directing sleeve having air directing means in endwise rotative engagement with said rack carrying sleeve and 25 being journalled about said alining section and said stud.

RANSAILLER J. JENKS.
